Act. 1.

UNITED STATES PATENT OFFICE.

JACOB DE S. FREUND, OF BEAVER, PENNSYLVANIA, ASSIGNOR TO AMERICAN CEMENT TILE MANUFACTURING COMPANY, OF WAMPUM, PENNSYLVANIA, A CORPORATION OF PENNSYLVANIA.

METHOD OF MAKING TILES.

1,168,492.

Specification of Letters Patent.

Patented Jan. 18, 1916.

Application filed December 27, 1912. Serial No. 738,848.

To all whom it may concern:

Be it known that I, JACOB DE S. FREUND, a citizen of the United States, and a resident of Beaver, in the county of Beaver and State of Pennsylvania, have invented a new and useful Improvement in Methods of Making Tiles, of which the following is a full, clear, and exact description, reference being had to the accompanying drawings, 10 in which—

Figure 1 is a sectional view through a plurality of tiles and forms showing one method of making the tiles; and Fig. 2 is a perspective view of one type of form for 15 carrying out my invention.

This invention relates to a method of making tiles in forms which are open at the top and bottom or at two sides thereof, and in which the tiles are laid one upon 20 another after they have been formed to allow them to set.

Another object of my invention is to form a part between adjacent tiles by means of a pulverized material which will be 25 absorbed by the tiles and provide a coating on both surfaces thereof.

The precise nature of my invention will be best understood by reference to the accompanying drawings, which will now be 30 described, it being premised, however, that changes may be made without departing from the spirit and scope of my invention, as defined in the appended claims.

In the drawings, the numeral 2 designates 35 a suitable bottom board or floor, 3 the molds, each of which, with the exception of the bottom mold, is provided with centering members 4, which are secured to the side members of the molds, and are provided 40 with lugs 4^a. Extending through the lugs 4^a on each end of each mold is a rod 4^b for securing the several parts of the mold to each other. These centering members 4 are tapered as indicated at 5 in order to center 45 the molds one upon the other, as hereinafter described.

6 designates the tiles which have been formed within the mold, and 7 the parting material between the several tiles.

50 The method is carried out as follows: The board or floor 2 is first coated with a powdered material 7 such as soapstone, soapstone and chalk, or any pulverized material in which the several particles will not adhere 55 to each other when they are moistened, but

which will adhere to cement or a cement mixture. The first mold 3 is then placed in position over the coated floor and the mold is filled with cement or a cement mixture, which is properly tamped. After it has been 60 tamped, the surplus material is struck off, so that the top of the tile or slab is flush with the top of the form. The top of the tile or slab, as well as the form, is then coated with the material indicated at 7, and 65 a second form is placed on top of the first form. The second form is then filled in a manner similar to which the first form was filled, the operation being repeated until a predetermined number of tiles has been 70 formed one above the other. The tiles are then permitted to set, and after they have set the forms and tiles are removed, the material 7 comingling with the adjacent tiles, and forming a coating on the outer 75 surfaces thereof.

Instead of using the powdered material alone, I can use a mixture of oil and powdered material which is painted or sprayed on the tiles to form the part.

The advantages of my invention result from the provision of a method by which I can make a plurality of tiles or slabs adjacent to each other with forms which are open at both sides or ends, by placing a 80 suitable parting material between the molds and tiles which form the top of one tile and the bottom of the other tile, and which parting material simultaneously forms a fac- 85 ing for the tiles.

I claim:

1. The method of forming a plurality of tiles or slabs one above the other, which consists in placing a mold open at the top and bottom on a suitable forming surface, 95 then filling the mold with a cement mixture, then striking off the surplus mixture, then coating the top of the formed tile with a parting substance which will be absorbed by the cement mixture but in which the particles will not adhere to each other, then placing a second mold open at the top and bottom on the first mold, then filling the second mold with cement, then striking off the surplus material, and repeating the operation until a predetermined number of tiles have been formed; substantially as described.

2. The method of forming a plurality of tiles or slabs one above the other, which 100

consists in placing a mold open at the top and bottom on a suitable forming surface, then filling the mold with a cement mixture, then striking off the surplus mixture, then **6** coating the top of the formed tile with soap-stone, then placing a second mold open at the top and bottom on the first mold, then filling the second mold with cement, then striking off the surplus material, and re-

peating the operation until a predetermined **10** number of tiles have been formed; substantially as described.

In testimony whereof, I have hereunto set my hand.

JACOB DE S. FREUND.
